(57) **CLAIM**

The ornamental design for a stool as shown, and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a stool showing my new design;

FIG. 2 is front view thereof;

FIG. 3 is a rear view thereof;

FIG. 4 is a right side view thereof, the left side view being a mirror image thereof;

FIG. 5 is a top view thereof;

FIG. 6 is a front perspective view of a stool showing a second embodiment of my new design;

FIG. 7 is front view thereof;

FIG. 8 is a rear view thereof;

FIG. 9 is a right side view thereof, the left side view being a mirror image thereof; and,

FIG. 10 is a top view thereof.

The broken lines depicting the feet of the stool form no part of the claimed design.

1 Claim, 10 Drawing Sheets
